(No Model.)

A. C. BRANTINGHAM.
DUST COLLECTOR.

No. 470,035.

Patented Mar. 1, 1892.

UNITED STATES PATENT OFFICE.

ALLEN C. BRANTINGHAM, OF COLUMBUS, OHIO.

DUST-COLLECTOR.

SPECIFICATION forming part of Letters Patent No. 470,035, dated March 1, 1892.

Application filed March 27, 1891. Serial No. 386,720. (No model.)

To all whom it may concern:

Be it known that I, ALLEN C. BRANTINGHAM, a citizen of the United States, residing at Columbus, in the county of Franklin and State 5 of Ohio, have invented a certain new and useful Improvement in Dust-Collectors, of which the following is a specification.

My invention relates to an improvement in dust collecting and separating devices, and 10 has particular relation to that class of dust collecting and separating mechanism employed in flour or other milling establishments.

The objects of my invention are to construct an improved device of this class by 15 means of which a thorough separation of the dust and air of a dust-laden air-current is obtained, to accomplish this object in a simple and reliable manner, to provide in connection therewith improved means for discharging the dust collected thereby, and to produce 20 said collecting and separating device in a compact and inexpensive form. These objects I accomplish in the manner illustrated 25 in the accompanying drawings, in which—

Figure 1 is a vertical sectional view of my improved dust-collector, taken on two planes, as indicated at xx and zz of Fig. 2; and Fig. 2 is a central sectional view taken through 30 the device on line yy of Fig. 1.

Similar letters and numerals refer to similar parts throughout the several views.

a represents the exterior casing of my improved dust-collector, which may be of the 35 rectangular form shown or of any other desired form. Of this exterior casing b b represent the side plates or faces, b' b' the end plates, and b^2 the top plate, said casing being supported upon a suitable base-frame c . Said 40 pieces b are, as shown in the drawings, provided with oppositely-located central openings, (indicated at d .) Through the casing a and centers of the openings d extends a fan-shaft d' , which may be journaled in any desirable frame-work in the outer side of said casing, and which carries, as shown at d^2 , a suitable belt-wheel.

Upon the shaft d' is mounted centrally between the side walls of the casing a the hub e 50 of a fan, which is adapted, as hereinafter described, to rotate within said casing. This fan consists of a number of suitable arms f ,

which radiate from the hub e and fan-vanes f' upon the outer portions of said arms. The fan thus constructed is partially incased by an inner casing g , preferably formed of sheet metal, said inner casing consisting of two disk-shaped plates which abut against the inner side walls b of the outer casing a , said disks being of a slightly-greater circumference than the circumference described by the outer ends 55 of the fan-vanes and being connected in their upper halves by a half-cylindrical cover-plate g' . The inner casing thus formed produces, as shown in the drawings, an inclosure of the upper half of the fan and two sides of the lower half thereof. The side disks g of the interior casing are formed, as shown in the drawings, with central openings, which are opposite the openings d of the exterior casing. As shown in the drawings, these side disks may be provided about their side openings with tubular extensions g^2 , which form 60 linings for the case-openings d . Formed through the disk g and casing side plates b at opposite points within a short distance of the periphery of the inner casing is a circular slot or mortise m , which, as shown, surrounds 65 the central openings d of the case.

Beneath the base-frame c and having its upper side communicating with the lower side of the fan-casing is the approximately V-shaped upper portion or mouth of a dust-receptacle i , which extends throughout the length of the lower side of the fan-case. This 70 dust-receptacle communicates on its lower side with the open upper side of a trap or discharge-chamber 12, the partially-cylindrical form of which is produced by the concave opposite sides thereof. From the under sides 75 of the concave sides of the discharge-chamber 12 lead the parallel side walls of a downwardly-extending dust-chute 13. The dust-chamber thus formed by the connection of mouth i , partial cylindrical chamber 12, and chute 13 is provided with end-closing plates 80 14. Through the center of the discharge-chamber 12 extends longitudinally the shaft 85 of a dust-trapping device k , the ends of which are journaled in the end plate 14 of the dust-discharge chamber, and from the periphery 90 of which project at equidistant points longitudinal flanges or carriers k' , which are of such width as when said shaft is rotated to 95 100

come into frictional contact with the interior surface of the concave sides of the discharge or trapping chamber 12. Rotary motion is imparted to the trap-shaft through a suitably-5 operated gear-wheel n upon one of the outer projecting ends of said shaft. The portions of the side casing-plates which are separated by the formation therein of the circular slots m may be connected together by suitable pins 10 or connecting-arms s , arranged at intervals in said slots.

The operation of my device is as follows: The fan being set in motion by the rotation of the shaft d' , currents of dust-laden air are 15 drawn into the fan-case through the central openings d , from whence said dust-laden air is driven by said fans toward the inner surface of the inner casing-plate g' . The force of the current being thus directed outward 20 from the outer ends of the fan-vanes, the dust or other heavy particles contained in the dust-laden air is driven against and follows the inner surface of the plate g' , while the purified air which is separated therefrom finds an outlet 25 through the slotted openings m of the casing, as indicated by the arrow in Fig. 2. The dust or heavier particles which follow the inner surface of the plate g' are carried downward and allowed to drop into the mouth i of the dust-chamber, from whence the dust is 30 deposited between the rotating flanges or arms k' of the trapping-chamber 12, and through the rotation of said arms the quantities of dust collected between them is finally 35 deposited through the chute 13.

From the construction and operation above described it will be seen that a suction of the dust-laden air is created toward the center of the fan through which said dust-laden currents enter the casing, and by the means 40 described the air and dust in said currents are readily separated, one being discharged through the chamber beneath and the other through the openings m near the outer side 45 or periphery of the case. As will readily be seen this method of separating the dust and air and collecting the former is exceedingly

simple and effective and is attained without the construction or use of complicated or expensive mechanism.

50

Having now fully described my invention, what I claim, and desire to secure by Letters Patent, is—

1. In a dust-collecting device, the combination, with the casing having an open lower 55 side, central inlet-openings d , and oppositely-located side openings m near the outer sides of said case, of a rotating fan-shaft d' , extending transversely through the center of said casing, and a fan upon said shaft, substantially 60 as specified.

2. In a dust-collecting device, the combination, with the outer casing a , having an open under side, central side openings d , and circular air-outlet openings m in said walls of said 65 case, and interior casing $g g'$, open on its under side and having openings opposite and corresponding with the case-openings d and n , of a rotating fan-shaft supported transversely through the side casing, as described, and a 70 fan upon said shaft, the upper half of which is inclosed by said outer casing, substantially as described.

3. In a dust-collecting device, the combination, with the casing having an open under 75 side, central side openings d , and oppositely-located side openings m near the outer portion of said casing, of a rotating fan-shaft d' , extending transversely through said casing, a fan mounted upon said shaft, a dust-chamber 80 beneath and communicating with said casing, consisting of a portion i , a chute 13, an intervening partially-cylindrical trapping-chamber 12, communicating with said mouth and chute, and a rotating shaft journaled 85 within said dust-trapping chamber, and conveying-flanges k' upon said shaft and rotated in frictional contact with the curved side walls of said trapping-chamber, substantially as specified.

ALLEN C. BRANTINGHAM.

In presence of—

BARTON GRIFFITH,
C. C. SHEPHERD.
